UNITED STATES PATENT OFFICE.

EBERHARDT A. VETTER, OF RICHMOND, VIRGINIA, ASSIGNOR TO CRAWFORD MANUFACTURING CO., INC., OF RICHMOND, VIRGINIA, A CORPORATION OF VIRGINIA.

CURTAIN BRACKET.

Application filed November 21, 1925. Serial No. 70,562.

This invention relates to curtain attachments for automobiles, and particularly to improved means for applying said curtains to the doors of automobiles so that the curtains will follow said door in the opening and closing movements thereof, even when said doors are pivotally mounted on a non-vertical axis.

It is old in the art to mount curtains to extend above the swinging doors of an automobile, so that said curtains will follow the door as it pivots around its hinges, thereby permitting unobstructed egress or ingress for passengers. When the doors of the automobile are mounted on hinges which are in straight vertical alignment, the opening pivotal movement of the door causes it to extend laterally of and at an angle to the body of the car, the curtain merely bending upon itself along a vertical line drawn through the axis of the aligned hinges, since, under such circumstances, there is no strain upon the fabric of the curtain.

Upon certain automobiles, of the present day, the doors thereof are pivotally mounted upon hinges which are not in exact vertical alignment, the lower hinge being positioned at one side of a vertical line drawn through the center of the top hinge. In most cases such structure is caused by the provision of an inwardly curved body, the curve beginning below the upper door hinge, the result being that the lower hinge is set inwardly with respect to the upper hinge.

Since the top of the door at all times forms the same angle with the line of the two hinges thereof, it is obvious that, in doors so mounted, when the door is fully opened, the outer corner thereof is lower than the

corner adjacent the car, and that said outer corner, moving outwardly and downwardly, comes to rest at a point which is further away from the bow of the car than would be the case if the hinges were positioned in vertical alignment. Since it is also true that, in cases of certain cars the stationary portion of the curtain is affixed to the body of the automobile adjacent to the door, and extends upwardly and is secured to the side bow under the top, it follows that the curtain structures at present in use would be ruptured by opening the door, in the absence of any preventative curtain and door connecting devices.

It is therefore the object of the present

invention to provide co-operating curtain-supporting means carried by the swinging door, and supported by the braces of the automobile, which means are operative to permit free swinging movement of the curtain when mounted on doors hinged on either a vertical or non-vertical axis, said means being automatically operable to prevent rupture of the curtain fabric even though the door is hinged on a non-vertical axis.

Other objects of the invention will be made apparent in the accompanying specification, when read in connection with the drawings forming a part thereof.

In said drawings:

Fig. 1 is a fragmentary perspective view of an automobile equipped with my invention, looking through the car and showing the curtains applied to the right hand side.

Fig. 2 is a fragmentary detailed perspective view showing portions of the co-operating curtain-supporting elements.

Fig. 3 is a cross section on the line 3-3 of Fig. 1, and,

Fig. 4 is a detailed view showing in full lines the position of an opened door mounted on non-vertically aligned hinges, and, in dotted lines, the position of an opened door mounted on vertically-aligned hinges.

Now referring specifically to the drawings, in which similar reference numerals indicate like parts throughout the several views, A indicates the body of an automobile equipped with front doors B and rear doors C, as shown in Fig. 1. The customary top 1 is mounted upon bows 2 which extend across the car, and the present invention contemplates means for properly securing a curtain 3 to the rear doors C carried by the body A. In my companion application filed of even date herewith, I disclose means for applying front curtains to the front doors B.

In order to better disclose the invention Fig. 1 shows an automobile in which the curtains on the left of the car have been removed, but the curtains on the right are in position. In the present drawings the invention is shown applied to a car of the Ford type, but it is obvious that the invention is equally applicable to any make of car.

Certain cars are provided with an apertured socket extending downwardly through the top surface of the door adjacent the edge

remote from the hinges, said socket being adapted to receive a vertically extending rod secured to the curtain, whereby the secured edge of the curtain will swing outwardly when the door is opened. In cars not equipped with such a socket I provide a socketed bracket 4 which is adapted to be easily secured to said door, and to receive and firmly retain the lower end of said rod, 10 as clearly shown in my said companion application heretofore referred to.

The rod 5 above referred to, is clearly shown in Figs. 1 and 2 of the drawings, the top of said rod entering a socket formed in 15 a plate 6, secured to the curtain 3, and provided with an ear 7 to which is rigidly connected a rod-arm 8. The top of the curtain 3 is made of two-ply material, and slits are provided therein to permit of the reception 20 of the arm 8, as illustrated in said Figs. 1 and 2. In cars of the Ford type a flat brace iron 9 is pivotally carried between adjacent bows 2, 2, and I provide a flat metal clip member 10, carrying a hooked portion 11 adapted to fit over said iron 9, as shown in 25 Fig. 2. The body of the member 10 is rigidly secured to the fabric, of the curtain 3, by staples or clips 12 extending through the fabric and said body, the top clip being 30 provided on its face with a curtain-fastener element 13 adapted to co-operate with a complementary element 14 carried on a flap 15 of said curtain, adjacent the point of attachment of the member 10 to the latter. 35 It is to be noted that, when the elements 13 and 14 are out of co-operative engagement, a slit 16 is formed in the top of the curtain adjacent the member 10, which slit is effectually closed by securing said elements 40 each to each.

The lower portion of said member 10 is provided with a laterally extending flange 17 apertured to receive the hooked end of the arm 8, said arm being provided at its extreme end with a flattened head 18 permitting free pivotal and tilting movement of the arm 8 with respect to the flange 17, when the elements 13 and 14 are disengaged. It is obvious that, in the structure described, 45 the curtain is secured to the member 10 which fits over the iron 9 to support the curtain.

In the structure as described, if the door C is mounted on hinges positioned in vertical alignment, the elements 13 and 14 may remain in co-operative engagement, since point x of the door will swing inwardly and outwardly and always remain at the same distance from the head 18 of the arm 8, the 50 curtain bending upon itself without danger of rupture. If the door is not mounted on hinges in vertical alignment however, but is mounted as shown in full lines in Fig. 4, the point x will swing outwardly and also drop downwardly, moving a greater distance 55

away from the point 18, thereby causing a strain upon the flap 15, if the fasteners 13 and 14 are engaged. If said fasteners are not engaged however the curtain will flex around the point 16', which may be properly reinforced, the hooked end of the arm 8 pivoting and tilting in the aperture in the flange 17. It will therefore be understood that the flap 15 is always pulled to disengage the elements 13 and 14, before the door C is 60 opened.

From the foregoing it will be evident that I have provided a structure which, while not interfering with the operation of curtains carried by doors of the ordinary type, will prevent rupture of curtains carried on doors pivotally mounted on hinges positioned in non-vertical alignment. In some cases the curtains are applied to the right hand doors only, and stationary curtains are mounted 65 upon the doors at the left of the car. While I have here described the invention as applied to cars of the Ford type, it is obvious that they are equally applicable to cars of any and all types.

Modifications of the structure herein illustrated will be suggested to those skilled in the art, but my invention covers all modifications falling fairly within the scope of the appended claims.

What I claim is:—

1. Means for mounting curtains on swinging doors of automobiles, comprising a rod secured to the door and extending upwardly in substantial parallelism therewith, a curtain having one side edge secured to said rod, a clip member secured to said curtain near its other side edge, said clip being provided at its top with a hooked portion adapted to extend over one of the bow braces 100 of the automobile, and at its bottom with a laterally extending flange and an arm secured at one end to the top of said rod and connected to the top edge of said curtain, the other end of said arm being pivotally 105 connected to said flange.

2. Means for mounting curtains on swinging doors of automobiles, comprising a rod secured to the door and extending upwardly in substantial parallelism therewith, a curtain having one side edge secured to said rod, a clip member secured to said curtain near its other side edge and being provided at its top with a hooked portion adapted to extend over one of the bow braces of the 110 automobile, and at its bottom with a laterally extending flange and an arm secured at one end to the top of said rod and connected to the top edge of said curtain, the other end of said arm being pivotally and 115 tiltably connected to said flange.

3. Means for mounting curtains on automobile doors carried on hinges positioned in non-vertical alignment comprising a rod secured to the door and connected to one side 120

edge of the curtain, a clip member secured adjacent the top of the curtain and near the other side edge thereof, said clip being provided at its top with a hooked portion extending over one of the bow braces of the automobile, a laterally extending flange carried by the bottom portion of said clip member, an arm secured at one end to the upper

portion of said rod, and tiltably connected at its other end to said flange, and a slit ¹⁰ formed in the top edge of said curtain adjacent said member, substantially as described.

In testimony whereof I affix my signature.

EBERHARDT V. VETTER.
